UNITED STATES PATENT OFFICE.

JAMES S. WHITAKER, OF SAN FRANCISCO, CALIFORNIA, ASSIGNOR OF ONE-HALF TO
H. C. WILSON, OF SAN FRANCISCO, CALIFORNIA.

BOAT-PROPELLER.

1,253,918.

Specification of Letters Patent. Patented Jan. 15, 1918.

Application filed September 20, 1916. Serial No. 121,234.

To all whom it may concern:

Be it known that I, JAMES S. WHITAKER, a citizen of the United States, residing at San Francisco, in the county of San Francisco and State of California, have invented new and useful Improvements in Boat-Propellers, of which the following is a specification.

This invention relates to mechanism for propelling small rivercraft, such as row boats and the object of the invention is to arrange upon the side of a boat, hinged oar members operative from the interior of the boat disposed to feather or fold one against the other when the same are moved to a forward position and to spread when moved to a rearward position, and thus propel the boat.

It is a further object of the invention to provide means for propelling a row boat wherein the oars, of a peculiar construction and of different sizes, may be easily and quickly attached, and whereby the said oars may be reciprocated in the arc of a circle by the occupants of the boat.

It is a still further object of the invention to provide a boat propelling means comprising oars arranged in pairs upon the opposite sides of the boat and to connect the same in such a manner that when the said oars are operated, one pair of oars will feather or swing toward each other in what may be termed a collapsing position, while the other pair of oars may be moved to an open position to fully contact with the water, and thus afford a continuous movement or travel of the boat as long as the oars are propelled.

With the above and other objects in view the improvement resides in the construction, combination and arrangement of parts set forth in the following specification and falling within the scope of the appended claim.

45 In the drawing:

Figure 1 is a side elevation of a row boat provided with my improvement,

Fig. 2 is a sectional view approximately on the line $\alpha-\alpha$ of Fig. 1,

50 Fig. 3 is a sectional view approximately on the line $\gamma-\gamma$ of Fig. 2, and

Fig. 4 is a sectional view approximately on the line $\zeta-\zeta$ of Fig. 2.

In the drawing, the numeral 1 designates

any ordinary small water craft such as, for instance, a row boat.

The boat 1 at the sides or gunwales thereof has secured thereto longitudinally extending strips 2, arranged diametrically opposite each other, and each of these strips 60 has pivotally connected therewith a rod 3, one end of said rod being offset and received in a suitable depression 4 in the said strips 2.

Pivotally secured to the strips 2, adjacent the opposite ends thereof, as at 5—5, are oar members 6, the handles 7 of said oars being provided with a plurality of spaced openings 8 whereby the said oars may be adjusted with relation to the strips 2, and 70 whereby one end of the oars will be extended downwardly along the side of the boat and the opposite edge may be projected above the gunwales of the boat. The downwardly projecting portions of the oars, indicated for distinction by the numerals 9, have one of their faces and which for distinction I will indicate as the rear face of the said oars, longitudinally channeled, as indicated by the numeral 10, and the lower 80

end of the oar at the channeled face thereof is provided with an outwardly extending lug 11 having a pair of upwardly projecting pintles 12. The inner wall of the channel may be provided with a plurality of 85 threaded openings, any one of which is adapted to receive the threaded shank of a headed element 13 that passes through a block 14, and this block is provided with a pair of downwardly extending pintles 15. 90 Each of the oars is provided with two blades 16—16, the said blades having their meeting edges formed with knuckles 17. The blades are attached to the oars by arranging the knuckles over the pintles 12, and 95 thereafter permitting the pintles 15 to enter the upper ends of their knuckles, the blocks 14 being then secured through the medium of the elements 13 to the respective oars.

The rear oar adjacent the lower end thereof 100 has pivotally connected thereto a rod 18', the said rod being arranged at an inclination and being pivotally connected to the forward oars. This connection can be made by having the forward end of the rod offset 105 and received in one of the plurality of openings in the handle of the said oar. The rear oars are connected by a bar 18, and if

desired the front oars may be likewise connected. The bar 18 is adapted to be grasped by the hand of the operator and to be reciprocated and it will thus be noted that both the forward and rear oars will be oscillated in unison but in a reverse direction, whereby the blades 16 of one of the pairs of oars will be contacted with the water but swung together when the same are brought to their forward position, while the blades of the opposite pair of oars being subject to contact by the water will move to their open position, and thus it will be noted that the boat may be propelled at a steady speed as the bar 18 is oscillated.

The boat is, of course, provided with the usual rudder 19 having an operating handle 20, and from the above description, taken in connection with the accompanying drawing, the simplicity of the device as well as the advantages thereof will, it is thought, be perfectly apparent to those skilled in the art to which such invention appertains without further detailed description.

Having thus described the invention, what I claim is:

In a boat propelling means, oars arranged in pairs at the opposite sides of the boat and adjustably connected with the said sides of the boat, each of said oars having an outwardly extending lug, a pair of upwardly projecting pintles upon each of said lugs, a pair of blades for each of the oars having knuckles receiving the pintles, a block member having a pair of downwardly extending pintles adjustably arranged one on each of the oars and the pintles thereof designed to be received in the knuckles of the pair of blades for each of the arms, an angularly disposed rod member loosely connected with each pair of oars upon the opposite sides of the boat, a swinging guide member for the oars on each side of the boat, and a connecting member providing an operating lever for two of the oppositely disposed oars upon the opposite sides of the boat.

In testimony whereof I affix my signature.

JAMES S. WHITAKER.
